UNITED STATES PATENT OFFICE.

RICHARD PAUL HEMMING, OF PHILADELPHIA, PENNSYLVANIA, ASSIGNOR
TO GEORGE W. ENNIS & CO., OF SAME PLACE.

DESIGN FOR A CURTAIN FABRIC.

SPECIFICATION forming part of Design No. 16,108, dated May 26, 1885.

Application filed April 16, 1885. Term of patent 8½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Curtain Fabric; and I do hereby declare that the photographic print accompanying this specification conveys to any one skilled in the art 5 to a clear understanding of the same, and is sufficient to enable such persons to use my invention.

The leading features of my design consist in the representation of two branches, A A, 15 formed to represent scrolls. These branches are connected at B, from which connection radiates a cluster of leaves. At the top of each

branch is represented a cluster of conventionalized hazel-nuts, D D D. At each side are shown a small branch and two conventionalized nuts D D. A full figure will show three conventionalized nuts on each of the small side branches, all of which is fully understood from the photographic print by those skilled in the art. 20

What I claim as my invention, and desire to secure by Letters Patent, is—

The design for a curtain fabric, as shown and described. 25

R. PAUL HEMMING.
